UNITED STATES PATENT OFFICE.

EMANUEL W. HARTMAN, OF MIAMI, FLORIDA.

APPARATUS FOR EXTRACTING GAS.

Application filed June 16, 1921. Serial No. 478,140.

This invention relates to an improvement in an apparatus for extracting gas, particularly in that type in which the gas is extracted from the bitumen containing material kept continuously in motion during its progress through the apparatus.

One object of this invention is to provide an apparatus in which the material from which the gas is to be extracted follows a substantially spiral course during its progress from the intake to the outlet.

Another object of the invention is to provide a gas extracting apparatus in which there is a free and unobstructed passage from the part carrying the treated material to the cracking tower.

A further object of the invention is to provide a gas extracting apparatus of circular form in which the material to be treated is moved over annular shelves by means of a plurality of rotary conveyors and in which the central portion of the apparatus acts as a cracking tower.

Other objects will appear from a consideration of the following description taken in connection with the drawings which form a part thereof and in which

Fig. 1 is a transverse sectional view of an apparatus embodying this invention;

Fig. 2 is a cross section of such apparatus taken on the line 2-2 of Fig. 1;

Fig. 3 is a cross section of the fire box taken on the line 3-3 of Fig. 1;

Fig. 4 is a plan view of one of the shelves on which the material to be treated is supported;

Fig. 5 is a section taken on the line 5-5 of Fig. 4; and

Fig. 6 is a view illustrating diagrammatically the relationship of the feed and discharge passages and the openings in the shelves.

Referring to the drawings reference numeral 10 is used to designate a furnace embodying one form of this invention having outer walls 11 and foundations 12 made of brick or other suitable non-heat conducting material. As shown particularly in Figs. 2 and 3 this furnace is circular in form. Supported on the foundation is a circular plate 13 slightly crowned at the center and provided with a plurality of ears 14 spaced at regular intervals around the circumference.

Supported upon the plate 13 are a plurality of annular members or shelves 15, one

of which is shown in detail in Figs. 4 and 5. Referring to those figures it will be noted that the shelf is an integral casting provided with two sets of ears 16 and 17, equal in number to and spaced the same distance 60 apart as the ears 14. In addition to the horizontal flat annular portion 18 of the shelf which supports the material to be treated, as will be described later, the shelf is provided with an inner annular flange 19 and 65 an outer annular flange 20, the lower set of ears 16 being fixed at the bottom of the second flange. In the furnace is a plurality of such shelves mounted one on top of another and fixed in place by means of bolts 70 passing through the ears as shown in Fig. 1.

Through the portion 18 of each shelf is provided an opening 21. The shelves are so positioned that the openings 21 are staggered, as illustrated in Fig. 6. Since the 75 shelves are identical in construction and thus interchangeable, it is obviously very easy to assemble them in any desirable relationship so as to vary the length of travel of the material through the furnace and it is also very 80 easy to replace a shelf should the occasion arise at any time.

A cover plate 22 formed similar in many respects to the shelves 15 is fixed in place by means of bolts passing through the ears 85 23 on the flange 24 of the cover plate and the upper ears 17 of the upper shelf 15. It will be noted that when the plates 13 and 22 and the shelves 15 are assembled as shown in Fig. 1 there is formed a retort A in which 90 the bitumen containing material is treated. Surrounding this retort A is an annular flue 25 formed between the walls 11 of the furnace on the one hand and the flanges 20 of the shelves 15 and the flange 24 of the 95 top plate 22 on the other hand. At the bottom of the furnace is an annular fire box 26 having a door 27 through which gas or other fuel can be fed to keep the retort at the proper temperature during the operation of 100 the furnace. The fire box 26 is defined by a metal ring 28 having a plurality of openings 29 therethrough so that the heated air can escape through these openings to the flue 25 and thence through the stack 30. The 105 retort is thus heated at both bottom and sides so that the material being treated is subjected to substantially the same heat during its entire travel. While any fuel may be used it has been found that gas fed 110

through one or more burners in the direction indicated by the arrows in Fig. 3 is the most satisfactory.

The material is moved through the retort by means of a conveyor mechanism supported upon and operated by an upright shaft 31 carried by bearings 32 mounted on a platform 33 depending from the center of the foundation 12. A flanged annular plate 34 fixed to the lower end of the shaft overhangs the bearings 32 and insures the proper location of the shaft. The chief weight of the shaft 31 is carried by I-beams 35 which rest on the walls 11 of the furnace. Between the plate 36 secured to the I-beams and a flanged cup-like plate 37 on the shaft are anti-friction bearings 38. The conveyor mechanism consists of a plurality of rotary conveyors 39, of the form shown particularly in Figs. 1 and 2, keyed to or otherwise fixed upon the shaft 31. Each of these conveyors comprises a sleeve or thimble 40 which surrounds the shaft 31 and which is connected to the annular conveying portion 41 by means of a spider 42. The portion 41 consists of a series of equally spaced pockets 43 defined by means of the annular flanges 44 and 45. The inner flange 44 is so arranged that it will project below the upper edge of the flange 19 of the shelf 15. The outer flange 45 is made shorter than the inner flange for a purpose to be described later.

The material is fed into the retort by some form of trap mechanism 46 which will prevent as much as possible the escape of gas from and entrance of air into the retort. The mechanism here shown is the same as that shown and described in detail in my copending application Serial No. 486,413 filed July 20, 1921. The trap is supplied through the chute 47 and the material is fed from the trap to the upper shelf 15 through the inlet passage 48. After the operation is completed the residue falls from the retort A through the passage 49 into the trap mechanism 50. This mechanism corresponds, except in size, to the trap 46 and carries the material to the discharge chute 51.

As shown in Fig. 6 the shelves 15 are mounted with the openings 21 staggered. Thus the conveyor which moves anti-clockwise according to Fig. 6 of the drawing, in transferring the material on one shelf from directly below the opening 21 in the shelf above to the opening 21, will move it slightly less than a full circle. If however it be desired to decrease the travel of the material for some reason or other the arrangement of the shelves can be changed to decrease the anti-clockwise distance between the openings in adjacent shelves. Fig. 6 shows the maximum travel possible with six shelves.

The shelves projecting inwardly from the walls of the retort define a central compara-

tively unobstructed cylindrical chamber 52 to which the gas which arises as a result of the heating of the material on the shelves 15 escapes freely in several ways, upwardly through the pockets 43, between the flanges 44 or beneath the flange 45 which is made shorter for that reason. The chamber 52 of the conveyor and the flange 19 of the shelf is connected by outlets 53 in the top plate to a pipe line 54 by which the gas is conveyed to the gas treating apparatus where the gasoline and other products are extracted. The top plate 22 is somewhat concaved so as to guide the gas away from the inlet passage 48 and toward the outlets 53. The chamber 52 is heated directly by the fire box 26 so that in case any heavy particles carried off with the gas fall to the bottom of the chamber they are further cracked under this heat and go out through the outlet 53. The chamber 52 thus acts as a cracking tower and will be referred to as such in the specification and claims.

In order to prevent the escape of gas around the shaft 31 a bushing 55 is provided comprising the collar 56 bolted to the top plate and projecting in a pocket 57 around the shaft which contains any suitable gasket material 58.

The feed trap 46 is operated by a vertical shaft 59 and the discharge trap is operated by a vertical shaft 60. Power is transmitted through the pulley 61 to a horizontal shaft 62, supported in bearing plates 63. The shaft 62 drives the shaft 31 thru the gears 64 and 65. The feed trap shaft 59 is operated from the shaft 31 by the gears 65 and 66, the shaft 67, supported in a bearing plate 68, and the gears 69 and 70. At the upper end of the discharge trap shaft 60 is fixed a bevel gear 71 which meshes with a bevel gear 72 on a horizontal shaft 73 carried by the bearing plate 74. The shaft 73 is driven from the shaft 62 by any suitable means, the pulleys 75 and 76 and belting 77 being illustrated in the drawing.

In the operation of this furnace the material is fed through the chute 47 to the trap 46 and thence through the passage 48 onto the upper shelf 15 falling into pockets 41 of the upper rotating conveyor 39. This conveyor carries the material around the upper shelf until the opening 21 is reached through which the material drops down to the second shelf where it is picked up by the second conveyor and the same operation is repeated until the material is carried by the lowest conveyor 39 to the outlet passage 49 through which it drops to the trap 50 and is discharged through the chute 51. During this travel the material is subjected to an intense heat from the fire box and flue and the gas driven off escapes to the cracking tower 52 and thence to the outlets 53 and the pipe line 54.

While one embodiment only has been shown and described I am not to be limited thereby since it is obvious that others could be made without departing from the spirit 5 and scope of my invention as set forth in the following claims.

Having thus set forth my invention that which I claim as new and for which I desire the protection of Letters Patent of the 10 United States is the following:

1. In an apparatus for extracting gas from bitumen containing material, a retort having a series of parallel annular shelves vertically arranged to form a vertical passage 15 through the center of said retort, said passage being in communication with said shelves, means for feeding the material to the upper shelf, each shelf having an opening therethrough, conveyor mechanism having 20 ing pockets for receiving and moving the material to be treated, along each shelf to the

opening therein and means for heating said retort, the gas extracted from the material escaping from the shelves into said vertical passage.

25

2. In an apparatus for extracting gas from bitumen containing material, a cylindrical retort having a series of parallel annular shelves vertically arranged to form a vertical passage through the center of said retort, said passage being in communication with said shelves, means for feeding the material to the upper shelf, each shelf having an opening therethrough, conveyor mechanism having 30 pockets for receiving and moving the material to be treated along each shelf to the opening therein and means for heating said retort, the gas extracted from the material escaping from the shelves into said vertical passage.

35

In testimony whereof, I affix my signature.
EMANUEL W. HARTMAN.
